UNITED STATES PATENT OFFICE

MARCUS J. NORTHBROOKE, OF NEW YORK, N. Y., ASSIGNOR TO INTERNATIONAL PHOSPHATE CO., A CORPORATION.

MACHINE FOR REDUCING SLAG FROM IRON-FURNACES FOR FERTILIZING PURPOSES.

No. 918,768.

Specification of Letters Patent. Patented April 20, 1909.

Application filed February 28, 1908. Serial No. 418,313.

To all whom it may concern:

Be it known that I, MARCUS J. NORTHBROOKE, a citizen of the United States, residing at New York city, in the county of New York and State of New York, have invented certain new and useful Improvements in Machines for Reducing Slag from Iron-Furnaces for Fertilizing Purposes, of which the following is a specification.

10 My invention relates to improvements in methods or processes and machines for the manufacture of phosphate from the residue of molten iron furnaces, as the resultant slag thereof, which heretofore, so far as my knowledge extends, is allowed to be thrown away as waste, whereby said slag may be utilized for fertilizing purposes; and it consists in the steps for carrying out said process in connection with such machine involving 15 the cutting action of knives mounted upon rolls or cylinders for reducing or pulverizing said slag in effecting its conversion for the intended purpose substantially as hereinafter more fully disclosed and pointed out by the 20 subjoined description and claims.

In the accompanying drawings illustrating the preferred form of my machine, for aiding the carrying out of the invention, Figure 1 is a side elevation thereof with parts broken 25 away disclosing more especially the knife or cutter equipped rolls or cylinders and adjunctive parts. Fig. 2 is an enlarged broken detailed end view showing in outline portions of the two rolls, the knife or cutter of one roll and one of its clearance grooves being also disclosed; one of the clearance grooves of the opposed roll also being shown. Fig. 3 is a vertical section taken on the line $x-x$ of Fig. 2. Fig. 4 is a like section produced on the line $y-y$ of Fig. 3.

In practicing my invention I provide a machine comprising principally a plurality of or numerous preferably steel rolls or cylinders 1, 1^a mounted in a suitable frame-work 2 with their undulatory or corrugated peripheries opposed to each other and equipped with numerous knives or cutters 3 arranged to cut in the plane of the axes of said rolls and standing out radially a short distance 45 therefrom. The knives or cutters of the two rolls or cylinders pass through intersecting lines or circles during the conjoint rotation of the latter, in order to effect a cutting or pulverizing action upon the slag or object fed 50 between said rolls, as is apparent.

I am aware that heretofore cylinders or rolls, having corrugated peripheries or surfaces but unequipped with cutters or knives have been employed for crushing purposes, but these do not answer my purpose of comminuting or pulverizing slag in its cold state, as discarded at molten iron furnaces, as I have found by practical demonstration, for the effective conversion or reduction of the slag to the desired or requisite fineness for utilization for fertilizing purposes as practiced by me.

The knives or cutters 3 are formed of approximately pyramidal outline in cross-section and introduced from the end of the rolls 70 into sockets or seats 3^a extending parallel with the axes of said rolls and opening out through one end of the latter, but stopping a short distance inwardly from the opposite end of the rolls thus forming an abutment 3^b 75 at that end for the retention in place of the opposed end of the knife or cutter. The cutter introducing end of the groove is provided with a closure preferably in the form of a plate a let into a recess b formed laterally in 80 the roll or cylinder for the retention of the closure itself from lateral displacement, it being held by screws c , or other suitable fastenings, against outward displacement, and accordingly securing the cutter or knife effect- 85 ively in its seat or socket, and by which arrangement the cutter may be readily removed whenever occasion may require as for removal, grinding or sharpening, or other cause. Said cutters or knives have their ef- 90 fective portions or points abruptly sloped with relation to what may be termed their shank-portions, with said points terminating in sharp edges as at d for comminuting or pulverizing the slag or object subjected to 95 the action thereof, especially in treating the slag as noted. In the peripheries of the rolls or cylinders are also formed clearance grooves e arranged at points opposite the cutters or knives 3 for the reception of their 100 points during the rotation of the rolls or cylinders for obvious purposes or as implied by their designation for clearance of the cutters or knives. One of said cylinders or rolls has its shaft suitably journaled in pillow-blocks 105 or bearings 5 of the frame-work 2 which is provided with lubricant-feeding cups 6, as usual. The other roll or cylinder is held yieldingly with relation to its fellow roll for obvious purposes by means of connected le- 110

- ver-members, 7 suitably fulcrumed upon the frame 2 and carrying in slots 8 therein bearings 9 between which are received the ends of the shaft or journal 1^b of the roll or cylinder, 5 said lever-members being subjected to the stress or tension of resilient members or springs 10. Said members or springs are themselves held between slides 11, one adapted to transmit the pressure received thereon 10 from said springs to said lever-members and the other slide being engaged and held in place by the action of a screw 12, all of said parts being suitably arranged and supported in position in the frame 2 as shown. 15 A suitable hopper-member 13 is applied to the frame 2 to provide for the proper feeding of the slag or material to the pulverizing or comminuting rolls 1^a as will be readily understood. 20 It will be readily seen that as the slag, fed in between the revolving knife or cutter equipped rolls or cylinders, is subjected to the cutting action of the knives thereof, said slag will be reduced or pulverized, suitably 25 converting it for utilization for fertilizing purposes. By thus subjecting the slag to a cutting action, as opposed to a crushing action, it is found that its reduction is rendered more effective for the purposes of my invention. 30

I claim:

1. A machine of the character described, comprising opposed rollers having undulatory peripheries, the elevations thereof being 35 equipped with cutters of general pyramidal outline, the valleys or hollows alternating with said elevations and having recesses for said cutters, said cutters having tapered points and their shanks flared from the base 40 of said points laterally, and said elevations having sockets receiving and conforming to said shanks and extending parallel with the axes of said rollers and each socket having an end-wall formed by a narrow portion of 45 one side of the roller and the entrance end of said socket terminating a short distance inwardly from the opposite side of the roller,

said entrance end of the socket having opposed or applied thereto a plate closure let into the side of the roller into contact with 50 one end of the cutter.

2. A machine of the character described, comprising opposed rollers having undulatory peripheries, the elevations thereof being equipped with cutters of general pyramidal outline, said valleys or hollows alternating with said elevations and having clearance recesses for said cutters said elevations also having sockets extending parallel with the axes of the rollers and each having one 60 end wall formed by a narrow portion of the roller at one side while the entrance end of the socket terminates a short distance inwardly from the opposite side of the roller, said entrance end of the socket having opposed or applied thereto a plate-closure let into the side of the roller into contact with 65 one end of the cutter.

3. A machine of the character described, comprising opposed rollers having their perimetric surfaces provided with cutters arranged parallel with their axes, said cutters having tapered points and their shanks flared from the base of said points laterally and having broad flat inner ends, said rollers 75 having sockets receiving and conforming to the outline of the shanks of said cutters and having a corresponding arrangement as said cutters to the roller-axes, each socket having one end-wall formed by a narrow-portion of 80 one side of the roller and the entrance-end of the socket terminating a short distance inwardly from the opposite side of the roller, a plate closure let into the side of the roller, in contact with one end of the cutter, and having its outer side flush with said side of the roller and its upper end stopping below the roller periphery and the point of the cutter. 85

In testimony whereof I affix my signature, in presence of two witnesses.

MARCUS J. NORTHBROOKE.
